Specification for Design.

Patented Mar. 1, 1921.

Application filed October 31, 1919. Serial No. 334,860. Term of patent 14 years.

To all whom it may concern:

Be it known that I, JOHN BEISWANGER, a citizen of the United States of America, and resident of Steubenville, county of Jefferson, State of Ohio, have invented a certain new, original, and ornamental Design for a Ramekin, of which the following is a specification.

In the accompanying drawing I have illustrated a ramekin, constructed in accordance with my invention, the same being of resistive transparent glass.

The figure is a perspective view of a ramekin, showing my new design.

Having thus described and illustrated my invention, I claim:

The ornamental design for a ramekin, substantially as shown.

Signed by me at Steubenville, Jefferson county, Ohio, this 22nd day of October, 1919.

JOHN BEISWANGER.
